UNITED STATES PATENT OFFICE.

ALGER FAST, OF LOS ANGELES, CALIFORNIA.

HEADLIGHT.

1,326,856.

Specification of Letters Patent. Patented Dec. 30, 1919.

Application filed February 12, 1918. Serial No. 216,723.

To all whom it may concern:

Be it known that I, ALGER FAST, a citizen of the United States, residing at Los Angeles, in the county of Los Angeles and State 5 of California, have invented a new and useful Headlight, of which the following is a specification.

This invention relates to headlights particularly for use in motor vehicles, and the 10 main object of the invention is to provide a headlight which will effectively illuminate the roadway in front of the vehicle, and will not project any rays into the space in front of the vehicle, above a given height, so as 15 to avoid the disagreeable and dangerous effects of the glare which is produced by ordinary headlights.

It has heretofore been attempted to reduce the glare from headlights by dimming the 20 lights, or by obstructing wholly or partially the rays passing from the upper part of the headlight. In either case there is a serious loss of illuminating power in the zone where illumination is required, and the expedient 25 of dimming or obstructing the upper part of the headlight is ineffective, as rays are reflected from the lower part of the reflector into the eyes of approaching persons, so that the glare is not satisfactorily eliminated.

30 My invention provides for effective elimination of any such undesirable reflections, while maintaining effective illumination within the required zone.

The accompanying drawings illustrate an 35 embodiment of my invention, and referring thereto:

Figure 1 is a side elevation of the headlight, showing by broken lines the manner in which the light is projected.

40 Fig. 2 is a vertical section thereof.

Fig. 3 is a front elevation, partly in section.

Fig. 4 is a section on line 4—4 in Fig. 2.

The headlight is provided with a casing 45 1, of suitable shape, for example, approximately cylindrical, (or if desired, approximately spherical) said casing having suitable supporting means, such as brackets 1' and having an aperture 2 in its front wall, 50 said aperture being preferably formed as a horizontal slot extending substantially the full width of the casing. The illuminating means, which may be an electric lamp 3 supplied with current by lamp cord 13, is 55 mounted in the upper forward part of said

casing, above the slot or aperture 2, and is provided with a concave or focal reflector 4 which may be of any suitable shape, for example, parabolic, so as to concentrate the light from the lamp 3 into a beam. The 60 lamp 3 may be adjustably mounted in reflector 4, by socket 5 and set screw 5'. A plane or substantially plane mirror or reflector 6 is mounted in the rear part of casing 1, in the path of the beam of light from lamp 3, and is disposed at such angle as to cause such beam of light to be reflected through the slot or aperture 2, in such manner that the upper edge of said beam, represented by line A in Fig. 1, is substantially horizontal so that 65 at no part of the beam thus projected forwardly from the headlight is the beam at sufficient height to enter the eyes of a person walking or driving in front of the vehicle. The aperture 2 in the front of the casing 1 is preferably provided with a glass pane 7, and an inclined shield 9 of glass or other transparent material is provided above said pane to shed water therefrom and prevent obscuring of the pane by water in rainy weather. I also prefer to provide a transparent section 15 of colored glass in the 70 lower part of the front pane 7; this section 15 being for example colored green in the right hand lamp and red in the left hand lamp of the vehicle, so that the headlights will also serve as right and left signal-lamps. Casing 1 may have a glass window 1' on one side to serve for illumination at the side of 75 the vehicle. The bottom of the casing 1 has an opening 28 to enable access to the interior of the casing, this opening being normally closed by a slide 29, preferably blackened on its upper surface to avoid reflection of any light therefrom.

The concave reflector 4 with the lamp 3 attached thereto, is preferably adjustable so as to vary the direction of incidence of the beam of light on the plane mirror 6, said reflector and lamp being mounted on a slide member 10 which slides in a curved guide-way 11 in the front wall of casing 1, suitable means such as clamp nut 12 being provided for holding the said parts in set position. The plane mirror 6 may also be adjustable in casing 1 by means of bolt 18 where head 18' engages in a curved keyhole slot 19 in mounting 20 on the back of said mirror, said bolt extending through a sleeve stud 22 and through a slot 23 in casing 1, 100 105 110

and provided with nut 24 for clamping the parts in set relation. An upper plane mirror 28 may be provided above the mirror 6 and having adjusting means consisting for example of a stud 29 in said mirror 28, having a screw 30 passing through slot 31 in casing 1 and fastened by a nut 32.

In the operation of the headlight, the light from lamp 2 is directed by the concave reflector 4 on to the plane mirror 8, and is reflected by the latter through the aperture 2, in the form of a beam of light whose upper limit, indicated by the line *a*, in Fig. 1 is at substantially uniform height above the ground, say about 40 inches, so as not to produce any glare in zone above that limit. Most of the light is directed straight forward, from the aperture, but some of the light is reflected downward so as to illuminate the ground for a sufficient distance in front of the vehicle for practical purposes, such illumination being more or less diffused and being exceptionally satisfactory in defining details of the roadway without fatiguing the eyes of the driver. Part of the light from lamp 3 is received directly by upper plane mirror 28 and is thereby reflected forward and downward through aperture 2 in such manner as to illuminate the roadway immediately in front of the vehicle.

What I claim is:

1. A headlight comprising a casing having an aperture in the lower part of its front, a lamp mounted in the forward part of the casing above said aperture, a focal reflector for directing the rays of said lamp rearwardly and downwardly, and a plane mirror at the rear lower part of the casing, mounted in such manner as to receive the rays so reflected and to reflect them forwardly through said aperture, the bottom of said casing being provided with a non-re-

flecting surface to prevent reflection of light forward and upward through said aperture. 45

2. A headlight comprising a casing having an aperture in the lower part of its front, and having a non-reflecting bottom member, a lamp mounted above said aperture, a focal reflector for directing rays from said lamp rearwardly and downwardly, a plane mirror at the lower rear part of the casing mounted in such manner as to receive the rays so reflected and to reflect them forwardly through said aperture, and 55 a mirror above the first named plane mirror and adapted to receive rays directly from said lamp and to reflect such rays forwardly and downwardly through said aperture.

3. A headlight according to claim 2, 60 wherein said lamp and focal reflector are angularly adjustable, and said first named plane mirror is angularly adjustable independently of the lamp and focal reflector, to vary the direction of the reflected rays. 65

4. A headlight according to claim 3, wherein the second named mirror is angularly adjustable independently of the lamp and of the first named mirror.

5. A headlight comprising a stationary 70 casing having an aperture in the lower part of its front, a lamp mounted in the forward part of the casing above said aperture, a focal reflector for directing the rays from said lamp rearwardly and downwardly, and 75 a plane mirror at the rear lower part of the casing, mounted to receive the rays so reflected and to reflect them forwardly through said aperture, said lamp and focal reflector being angularly adjustable in said casing 80 to vary the direction of the reflected rays.

In testimony whereof I have hereunto subscribed my name this 6th day of February, 1918.

ALGER FAST.
